(57) **CLAIM**

(21) Appl. No.: **29/146,658**

The ornamental design for a compressor for air conditioners for vehicles, as shown and described above.

(22) Filed: **Aug. 15, 2001**

DESCRIPTION

(30) **Foreign Application Priority Data**

Feb. 19, 2001 (JP) 2001-008581

FIG. 1 is a front view of a compressor for air conditioner of vehicles, according to the design.

(51) LOC (7) Cl. **15-02**

FIG. 2 is a rear view of the compressor, as shown in FIG. 1.

(52) U.S. Cl. **D15/9**

FIG. 3 is a right side view of the compressor, as shown in FIG. 1.

(58) Field of Search D15/7-9; D23/325,
D23/354; 418/259, 67

FIG. 4 is a left side view of the compressor, as shown in FIG. 1.

(56) **References Cited**

FIG. 5 is a top view of the compressor, as shown in FIG. 1.

U.S. PATENT DOCUMENTS

FIG. 6 is a bottom view of the compressor, as shown in FIG. 1.
